Primary Examiner — Selina Sikder*(74) Attorney, Agent, or Firm* — Jenkins, Wilson, Taylor & Hunt, P.A.**CLAIM**

The ornamental design for a light emitter package, as shown and described.

DESCRIPTION

FIG. 1 is a top perspective view of a light emitter package showing our design;

FIG. 2 is a first side view thereof;

FIG. 3 is a second side view thereof, opposite the view of FIG. 2;

FIG. 4 is a third side view thereof;

FIG. 5 is a fourth side view thereof, opposite the view of FIG. 4; and,

FIG. 6 is a bottom plan view thereof.

The broken lines are included for the purpose of illustrating environment of the design and form no part of the claimed design.

1 Claim, 4 Drawing Sheets(56)
